UNITED STATES PATENT OFFICE.

JOHN J. CAMPBELL AND FERDINAND J. SPANG, OF BUTLER, PENNSYLVANIA, ASSIGNORS TO SPANG AND COMPANY, OF BUTLER, PENNSYLVANIA, A CORPORATION OF PENNSYLVANIA.

WIRE CLAMP.

Application filed December 15, 1921. Serial No. 522,517.

To all whom it may concern:

Be it known that we, JOHN J. CAMPBELL and FERDINAND J. SPANG, citizens of the United States, and both residents of Butler, in the county of Butler and the State of Pennsylvania, have jointly made a new and useful Invention in Wire Clamps, of which the following is a specification.

This invention relates to wire line clamps and has for an object to produce such a clamp which is rugged and durable, and which is easily manipulated and is effective in operation.

A further object is to produce a clamp in which improved means are employed for controlling the relative movement of the clamp arms or jaws and for insuring the proper relative positioning when the jaws are closed.

20 A further object is to produce a clamp in which means are employed for reducing the friction between the moving parts and at the same time increasing the durability and ruggedness of the clamp.

25 These, and other objects which will be made more apparent throughout the further description of the invention, are attained by means of apparatus embodying the features herein described and illustrated.

30 In the drawings accompanying and forming a part hereof, Figure 1 is a plan view of a clamp embodying our invention. Figure 2 is a sectional view along the line 2-2 of Fig. 1. Fig. 3 is a sectional view along the line 3-3 of Fig. 1. Fig. 4 is a sectional view along the line 4-4 of Fig. 3. Fig. 5 is a sectional view along the line 5-5 of Fig. 3 and Fig. 6 is a rear view of the clamp, portions being shown broken and in section for convenience of illustration.

45 The clamp illustrated includes jaws or clamp arms 7 and 8, a back plate 9, a clamp tightening device 10, and jaw-positioning means or guiding pawls 11. Each clamp arm is provided with a liner-way, and a liner 12 of the usual construction is mounted therein and, as shown, is held in place by means of a set screw 13 which extends through an unthreaded aperture in the clamp arm and is screwed into a threaded aperture provided in a boss formed on the rear face of the liner. A link-engaging hook 37 is integrally formed with each clamp arm and is so located with relation to the liner that the effective point of sus-

pension of the clamp is in line with the axis of the liners when the clamp arms are closed.

Each arm is pivotally connected to the back plate 9 by means of a separate pin 14. The back plate and the arms are so formed that the pins are so reinforced throughout their length that they are substantially relieved of shear and cross-bending strains occasioned by the wire-clamping operation. Each pin forms, in effect, a roller bearing between the back plate and its associated arm.

As illustrated, the back plate is provided at each end with two-pin-receiving lugs 15. These lugs are located on opposite sides of the plate and the pin-receiving apertures of each set of lugs are, of course, aligned. Each clamp arm is also provided with two pin-receiving lugs 16 so spaced that the back plate 9 fits between them. As illustrated in Fig. 5, the back plate is so constructed that it engages each pin 14 throughout the entire length of the back plate. Each clamp arm is also so constructed that it engages the portion of the co-operating pin located between the lugs 15 of the back plate. This is accomplished by so forming the ends of back plate 9 between the lugs 15 that each end partially encircles one of the pins 14, and by providing a sector-shaped boss 17 on each clamp arm, so located with relation to the back plate that it projects between the lugs 15 and engages the pin throughout the intermediate portion, located between the lugs 15-15 of the back plate. The pin-engaging face of each boss 17 is arranged to engage a substantial portion of the pin and the boss is so located with relation to the pin-engaging portion of the back plate that the intermediate portion of the pin engaged by the bearing face of the boss is located opposite to the pin-engaging portion of the back plate between the lugs 15. Each arm is also provided with an arc-shaped way 19 into which the curved end of the back plate projects. As shown, the way is so formed that the curved pin-engaging portion of the back plate partially extends into the way even when the arms are in the closed position illustrated in Fig. 5, and the arrangement is preferably such that the projecting ends of the clamp arms reinforce the back plate between the lugs 15. With the arrangement

100
105
110

of back plate and arms above described, and illustrated in Fig. 5, the pins 14 are relieved of cross-bending strains and the shearing strains, to which hinge pins are ordinarily subjected when the clamp is closed and pressed into gripping engagement with a line wire, and while the pins 14 hold the clamp arms in place on the back plate, they function as roller bearings rather than hinge pins. This is occasioned by the fact that the lugs 17 operate to transmit the thrust to the back plate and the intermediate portion of each pin merely operates as a strut or compression member, since its active portion is engaged on one side by the pin-engaging face of the lug 17 and on the other side by the pin-engaging face of the curved-over end portion of the back plate.

In the drawings, we have shown the clamp provided with two guiding pawls 11 which are so located and arranged that the arms 7 and 8 always assume the proper relative position when closed. As shown, each pawl consists of a cup 20 having a substantially spherical head 21. The cup is slidably mounted in a recess in the arm 8 and the portion 21 projects beyond the recess. The cylindrical portion of the pawl is of such dimension that it is guided by the aperture throughout a short range of longitudinal motion. It also encloses a coil spring 22 which operates between it and the inner end of the aperture to yieldingly press the cup outwardly and hold the head 21 in engagement with an aperture 23 formed in the arm 7. This aperture is provided with a semi-spherical base on which the spherical head 21 rides during pivotal motion of the arms about the pins 14. While it is apparent that the pawls 11 illustrated shift one arm longitudinally, with relation to the other arm during the opening movement, it will also be apparent that the range of longitudinal movement is extremely small and that the pawls always operate to return the arms to the same relative position when they are closed, and insure the proper positioning of the liners 12 with relation to each other when they are moved into gripping engagement with a line wire. The pawls are extremely effective in operation and in addition they are simple to manufacture and may be readily installed without the necessity of materially modifying the construction of the jaws or clamp arms.

The clamp-tightening device generally referred to by the numeral 10 consists of a tightening screw 25, the shank of which is reciprocatively mounted in a saddle 26 and is provided with an arm-engaging head 27. The threaded end of the shank is engaged by a hand-operated tightening nut 28. The saddle is pivotally secured to one clamp arm so that the T-head 27 of the tightening screw may be moved into or out of line with

a recess or socket 29 formed on the other clamp arm. In the drawings, the saddle is shown mounted on the clamp arm 8 which is bifurcated at its free end and is provided with saddle-mounting pins 30. Each mounting pin is suitably mounted on one fork of the bifurcated end of the arm and the saddle is provided with pin-engaging extensions 31 which extend parallel with the screw-receiving way or guide 32 and each of which is provided with an aperture adapted to receive the projecting end of one of the pins 30. In order to relieve the pins of the shearing strains, the saddle is provided with two lugs 33, each of which is adapted to engage a cylindrical boss formed at the ends of the bifurcated portion of the clamp 8 and so arranged that the cylindrical surface thereof is concentric with the pin 30 carried thereby.

The guide 32 for the tightening bolt is located between the extensions 31 and also between the lugs 33 and projects between the forks of the bifurcated end of the arm 8. The screw 25 is held against rotation therein by a suitable key and the tightening nut is screwed onto the threaded end of the screw and is rotatably held in place on the saddle by one or more balls 34 located in a suitable race formed in a cylindrical extension of the saddle and the nut. After the line wire 35 is located in place between the liners 12, the clamp arms 7 and 8 are moved toward the closed position and the saddle 26 is swung about the pivot pins 30 to bring the T-head 27 of the tightening screw in line with the recess or socket 29. This may be accomplished by means of a handle 36 formed integrally with the T-head 27. The nut 28 is then turned for the purpose of drawing the screw 25 inwardly, relatively to the saddle, and of thereby moving the T-head into engagement with the clamp arm 7. As this screwing operation continues, the clamp arms are moved together and the liners 12 are forced into gripping engagement with the line wire 35, the gripping force, of course, being dependent upon the amount of force applied to the nut 28 in drawing up the tightening screw 25. As shown, the saddle is provided with a thrust bearing 38 for the base of the nut 28 so arranged that the ball or balls 34 are relieved of strain during the tightening operation.

In releasing the clamp, the tightening nut is turned in the opposite direction so that the T-head 27 of the tightening screw moves away from the saddle. As soon as the head is moved out of engagement with the groove 29, the head may be swung outwardly by means of the handle 36, and the line 35 may be withdrawn from between the clamp arms.

While we have described and illustrated but one embodiment of our invention, it

will be apparent to those skilled in the art that various changes, modifications, substitutions, additions and omissions may be made in the apparatus illustrated without departing from the spirit and scope of the invention, as set forth by the appended claims.

What we claim is:

1. A wire line clamp comprising a back plate, clamp arms, a separate pin for pivotally securing each arm to said plate, said arms and plate being provided with pin encircling lugs and additional pin engaging surfaces so formed as to substantially relieve the pins of shearing strains when the arms are forced to a closed position.
2. In combination in a line clamp, a back plate, two clamp arms and a pivot pin connecting each arm to the back plate and forming a roller bearing between each clamp arm and said plate for holding each arm in pivotal relation with the plate and means for securing the arms in clamping position.
3. In combination in a line clamp, a back plate, two clamp arms, a separate pin for holding each arm in hinged relation to said plate, said plate and said clamp arms being provided with opposed faces engaging diametrically opposite sides of the pins whereby the pins are substantially relieved of shear and means for locking the arms in clamping relation.
4. In combination in a wire line clamp, a back plate, two clamp arms, a separate pin for pivotally securing each arm to said plate, said arms and said plate each being so constructed as to provide a bearing on the pin substantially throughout the length of each pin whereby the pins are relieved of shearing stresses, and a guiding pawl yieldingly mounted on one of said arms and engaging a recess formed in the other arm, and means for holding said arms in clamping relation.
5. A wire line clamp comprising a back plate, clamp arms, a separate pin for pivotally securing each arm to said back plate, means formed integrally with the back plate whereby each pin is engaged by the back plate throughout the length of the back plate, and means formed integrally with each arm whereby each pin is engaged by an arm throughout the width of the arm.
6. In combination in a wire line clamp, two clamp arms, each provided with a pin receiving lug at each side thereof and an intermediate pin engaging lug extending axially of said first mentioned lugs and substantially the entire width thereof, a plate located between the pin receiving lugs of each clamp arm, and provided at each end with two spaced pin receiving lugs axially aligned with the pin receiving lugs of the adjacent clamp arm and a pin engaging lug extending axially of the pin receiving lugs and between each set of pin receiving lugs,

a separate pin for pivotally securing each arm to said plate, and means for securing the arms in clamping relation.

7. In combination with the relatively movable clamp arms of a wire line clamp, a locking means for said clamp comprising a tightening screw having an arm engaging head, a saddle pivotally mounted on one of said arms and having a way in which said screw is reciprocatively mounted, means operatively secured to said saddle for moving said screw in said way, and lugs formed on said saddle for engaging the mounting arm thereof and for transmitting the tightening force exerted by said screw directly to said arm.

8. In combination with the relatively movable clamp arms of a wire line clamp, a locking device for said clamp arms comprising a tightening screw having an arm-engaging head, a saddle pivotally mounted on one of said arms having a thrust bearing engaging the mounting arm and provided with a way in which the shank of said screw is mounted, a tightening nut mounted on said screw, and means for rotatively holding said nut in place on said saddle.

9. In combination with the relatively movable clamp arms of a wire line clamp, a locking device for said clamp arms comprising a tightening screw having an arm-engaging head formed on the shank thereof, a saddle pivotally mounted on one of said arms having a thrust bearing engaging said mounting arm, and provided with a way in which the shank of said screw is reciprocatively mounted, a tightening nut screwed onto the shank of said screw, and a ball for operatively securing said nut in place on said saddle.

10. A wire line clamp comprising a back plate, clamp arms and a separate pin for pivotally securing each arm to said back plate, said back plate and arms being so formed that each arm engages one pin throughout substantially the entire width of the arm and the plate engages each pin throughout substantially the entire length of the plate, whereby each pin is substantially relieved of shearing strains when the arms are forced to a closing position.

11. A wire line clamp comprising a back plate, clamp arms, a separate pin for pivotally securing each arm to said back plate, said arms and said back plate being so formed that each arm forms a bearing for one pin substantially throughout the width of the arm and the plate forms a bearing for both pins substantially throughout the length of the plate, and a projecting lug formed on each arm and reinforcing the adjacent pin bearing on the plate when the arms are forced into a line clamping position.

12. A wire line clamp comprising two clamp arms, a back plate, and a separate pin

for pivotally securing each arm to said plate, said plate being provided with pin receiving lugs and so formed that it engages each pin throughout substantially the entire length 5 of the plate, and each arm being so formed that it engages its pivot pin through substantially the entire width of the arm, and being provided with at least one pin receiving lug and with a lug extending longitudi-

nally of the pin and engaging the adjacent 10 side of said plate, and means for forcing the arms to a closed position.

In testimony whereof, we have hereunto subscribed our names this 12th day of December, 1921.

JNO. J. CAMPBELL.
FERD J. SPANG.
